UNITED STATES PATENT OFFICE.

GEORGE R. FARRELL, OF CAMBRIDGE, MASSACHUSETTS, ASSIGNOR TO M. W. CARR & CO., OF SOMERVILLE, MASSACHUSETTS, A FIRM COMPOSED OF LOUIS B. CARR, EUGENE P. CARR, AND FRED M. CARR, OF SOMERVILLE, MASSACHUSETTS.

FRAME FOR BAGS, &c.

SPECIFICATION forming part of Letters Patent No. 747,158, dated December 15, 1903.

Application filed August 25, 1903. Serial No. 170,734. (No model.)

To all whom it may concern:

Be it known that I, GEORGE R. FARRELL, of Cambridge, in the county of Middlesex and State of Massachusetts, have invented certain new and useful Improvements in Frames for Bags and Similar Articles, of which the following is a specification.

This invention relates to improvements in means employed to attach a bag or similar article to its frame or top, and has for its object to provide means which will be neat in appearance, easily operated, inexpensive, and very strong and durable.

The invention consists of the novel construction, arrangement, and combination of parts, as will be fully described hereinafter and set forth in the claims annexed hereto, and it is carried out substantially as illustrated on the accompanying drawings, which form an essential part of this specification, and whereon like characters of reference refer to like parts wherever they occur on the different parts of the drawings.

On the drawings, Figure 1 represents a perspective view of a circular frame or top of a bag or purse and showing the means employed to attach the bag or purse to said frame or top, but showing such means detached from the frame or top. Fig. 2 represents a side elevation of a bag or purse provided with a frame or top similar to that shown in Fig. 1, but showing the bag or purse attached to its frame or top by my improved means of attachment and the frame or top in section. Fig. 3 represents a sectional end elevation of a hand-bag or valise, showing the bag or valise attached to its frame in accordance with my invention.

Referring to the invention as illustrated in Figs. 1 and 2, in which the invention has been illustrated as applied to the attachment of a bag or purse to a perforated circular frame or top, the bag or purse 1 may be made of cloth, leather, netted fabric, beadwork, or of any other flexible material and may be made plain or ornamented, as is desired. The frame 2 is provided with the annularly inwardly projecting flange 3, which terminates

in a series of projecting prongs or pins 4, arranged around the inner edge of the flange, which prongs are for a purpose to be fully understood by the complete description of the device herein contained. This frame 2, its flange 3, and prongs 4 are preferably made of metal, but may be made of any other suitable material.

A cover 5 for the bag or purse is hinged or otherwise attached to the frame 2, it having been shown on the drawings as hinged thereto, as at 6, and the frame is provided with any suitable catch 7 now in common use. As the particular construction of the frame, the cover, or of the catch to be used upon the bag or purse form no essential parts of my invention, the construction of said parts may be varied at will without departing from the spirit of my invention, which relates only to the manner of attaching the bag or purse to the frame or top desired to be used. Although I have illustrated the frame of the bag or purse as being circular, it will be understood that the same might be varied so as to be square, hexagonal, oval, oblong, or any other desired shape.

A holding-ring 8, preferably made of metal and of a size and shape to rest upon the top surface of the inwardly-projecting flange 3 of the frame, is used. The material from which this ring is made is preferably made round in cross-sectional area; but it may be made in any other suitable shape and of any other material. A clamping and finishing ring 9 is also used. This ring is also preferably made of metal which is flat, and is preferably substantially the size and shape of the upper surface of the flange 3, as shown, and so as to fit comparatively close within the frame 2.

In using my above-described invention in attaching a bag or purse to its frame one first firmly secures the upper end of the bag or purse to the holding-ring 8 by sewing the same thereto or by otherwise attaching it thereto in some similar or equivalent manner. He then passes the bag or purse through the perforation in the frame until the hold-

ing-ring 8, with the bag or purse attached firmly thereto, will rest upon the upper surface of the flange 3 and the prongs 4, which project upward from the inner edge of the flange, have passed through the fabric of the upper part of the bag or purse. If the nature of the bag or purse is such that the entire bag or purse cannot pass through the perforation in the frame, its upper end may be 10 passed through the frame from the under side prior to attaching the holding-ring to the upper edge thereof. After the holding-ring 8, with the bag or purse attached thereto, rests upon the upper surface of the flange and the 15 projecting prongs have pierced the upper end of the bag or purse the person places the clamping or finishing ring within the frame and upon the holding-ring 8, thus covering the holding-ring and the upper edge of the 20 bag or purse. He then turns the projecting prongs 4 outward and downward against the upper surface of the clamping-ring, which causes the holding-ring, with the attached upper edge of the bag or purse, to be firmly 25 clamped and held between the upper surface of the flange 3 and the under surface of the clamping-ring 9. It will also be seen that the prongs 4, passing through the upper end of the bag or purse, will assist materially in 30 holding the bag or purse attached to the frame and that the clamping-ring gives a finished appearance to the frame, as it covers the upper edge of the bag or purse which would otherwise be liable to be unsightly and 35 ragged in appearance. By this manner of attaching the bag or purse to its frame there is nothing on the exterior or exposed part of the frame to indicate the attachment of the bag or purse thereto. There are no rivets used, and 40 the bag or purse may be quickly and easily removed from its frame and replaced by a new one if it should become worn out or ruined. Thus an expensive or valuable frame may be used for a number of bags or purses, if so desired. 45 This manner of attaching the bag or purse to its frame is not only applicable to a solid or ring-shaped frame or top with a cover to cover the perforation in said frame and as shown in Figs. 1 and 2, but it is equally applicable to a frame made in two or more pieces pivotally or otherwise attached to each other and folded or pressed together when closed similar to the frames of hand-bags and valises now in common use, and I have shown 50 my invention applied to such a bag in Fig. 3 55 of the drawings.

In Fig. 3 the frame of the bag has been shown in two pieces 10 and 11, hinged together, as at 12, so that the frame may fold upon itself when the bag is closed, and it will be understood that the holding-ring 8 and clamping or finishing ring 9 will also be divided into the same number of parts as that of the frame.

If it is desired to reduce the cost of attaching the bag or purse or valise to the frame and it is immaterial as to the appearance of the interior of the bag, purse, or valise, the clamping and finishing ring 9 may be dispensed with and the prongs 4 will then be 60 bent outward and downward directly against the top of the holding-ring 8 with its attached bag, purse, or valise and the holding-ring thus be clamped against the surface of the flange on the frame and between said flange 75 and the prongs.

Having thus fully described the nature, construction, and the operation of my invention, I wish to secure by Letters Patent and to claim—

1. In a bag frame or top, a holding-ring to which the upper end of the bag or similar article is attached, and projecting prongs upon the edge of the frame or top adapted to be bent downward to clamp the holding-ring 85 firmly against the frame or top.

2. In a bag frame or top, a holding-ring to which the upper end of the bag or similar article is attached, projecting prongs upon the frame or top adapted to be bent downward to 90 clamp the holding-ring firmly against the frame or top, and a clamping and finishing ring interposed upon the holding-ring and between the holding-ring and clamping-prongs.

3. In a bag frame or top, a flange on the 95 frame or top, a holding-ring to which the upper end of the bag or similar article is attached, projecting prongs on the edge of the flange on the frame or top, adapted to be passed through the upper part of the bag or 100 similar article and bent downward to clamp the holding-ring firmly against the surface of said flange, and a clamping and finishing ring interposed upon the holding-ring between the holding-ring and clamping-prongs. 105

In testimony whereof I have affixed my signature in presence of two witnesses.

GEORGE R. FARRELL.
